CLAIM

The ornamental design for a hamstring curl device, as shown and described.

DESCRIPTION

FIG. 1 is a front, top perspective view showing the new, original, and ornamental design of a hamstring curl device; FIG. 2 is a front elevation view thereof; FIG. 3 is a rear elevation view thereof; FIG. 4 is a right elevation view thereof; FIG. 5 is a left elevation view thereof; and, FIG. 6. is a top plan view thereof, the bottom side being a mirror image of the top side. The broken lines in FIGS. 1, 2, 3, 4, and 5 form no part of the claimed design.

1 Claim, 4 Drawing Sheets
